UNITED STATES PATENT OFFICE.

JOSHUA W. ATLEE, OF RIVERTON, NEW JERSEY.

PORTABLE CARGO BATTEN-CLEAT.

1,252,533.

Specification of Letters Patent.

Patented Jan. 8, 1918.

Application filed July 20, 1917. Serial No. 181,730.

To all whom it may concern:

Be it known that I, JOSHUA W. ATLEE, a citizen of the United States, and a resident of Riverton, in the county of Burlington and 5 State of New Jersey, have invented certain new and useful Improvements in Portable Cargo Batten-Cleats, of which the following is a description.

My invention relates to brackets or batten 10 cleats which are adapted to be secured to the flanges of the vertical ribs of the hull of a vessel to support cargo battens such as are usually provided within the hold of a vessel to prevent the cargo from coming in contact 15 with the sides or skin of the vessel, or other structural parts.

The objects of the present invention are to provide a portable cargo batten cleat which may be readily attached at any point or position 20 on the flange of the angle bars or ribs of the hull or other structural parts, without providing said angle bars or ribs with holes, projections, or any other special construction by means of which the cleat is supported thereon; to avoid the use of bolts, nuts 25 or wrenches in attaching or removing the cleats from their supports; to provide a cleat which may be very quickly and easily fixedly secured to, or removed from its support.

Further objects of my invention are to provide cleats which may be rigidly frictionally secured at any point on the flange or web of an angle iron or rib at such an 35 angle thereon as to support the batten parallel to that portion of the side or hull of the ship adjacent the batten, and to provide such frictionally supported cleats as are adapted to be attached to the different forms 40 or shapes or types of angle bars or ribs usually employed in ship building.

Other objects of my invention will appear in the specification and claims below.

In the drawings forming a part of this 45 specification and in which the same reference characters are employed throughout the various views to indicate the same parts.

Figure 1 is a plan view of a batten cleat embodying my invention, secured to an angle bar, shown in horizontal cross-section, and showing a batten supported on said cleat;

Fig. 2 is a side elevational view of the same on the line 2—2 of Fig. 1, with the 55 batten, side of the ship, and one flange of the angle bar in vertical cross-section;

Fig. 3 shows the same batten cleat in the position in which it is secured to the flange or rib of an angle bar or rib to support the batten parallel with the side of the ship 60 at the point where the angles between the webs are obtuse angles;

Fig. 4 is a similar view to Fig. 1 of a slightly modified construction adapted to support a batten transverse to the forward 65 edge of the support or web;

Fig. 5 is a view similar to Fig. 1, of a further modified form of batten cleat adapted particularly for use in connection with a plain angle iron bar or rib also commonly 70 employed in ship building;

Fig. 6 is a sectional view on the line 6—6 of Fig. 5;

Fig. 7 is a plan view, similar to that of Fig. 3, showing the same cleat located at another portion of the vessel where the supporting web on the angle bar makes its greatest angle with the side of the vessel;

Fig. 8 is a sectional view on the line 8—8 of Fig. 7.

Fig. 9 is a view, similar to Fig. 1, of another modification of my invention, particularly adapted for use with "bulb" webs or supports, frequently employed in ship building;

Fig. 10 is a sectional view on a line 10—10 of Fig. 9 showing a side elevation of the supporting cleat shown in Fig. 9;

Fig. 11 is a view, similar to Figs. 3 and 7, showing this embodiment of my invention 90 secured to a bulb angle bar or rib at a point where the flange makes its greatest angle to the side of the vessel; and

Fig. 12 is a perspective sketch showing a portion of the hold or hull of a vessel showing one form of my improved batten cleat (that shown in Figs. 5 to 8) in position in supporting the battens thereon.

Referring now to the first modification of my invention, as illustrated in Figs. 1 to 3, 100 a rib or support 1, composed of two angle irons riveted together, shown in horizontal cross-section, is secured by rivets 2 to the side 3 of the ship. The flange 4 of the rib or support 1 is the one to which my cleat is 105 adapted to be secured. Sometimes these angle irons are riveted together to make a substantially Z-shaped rib, as shown in Fig. 1, but sometimes they are so riveted together as to make a channel or U bar construction. 110 In either of these constructions, the outer flange 4 is always parallel to the other

flange thereof which is secured to the side 3 of the ship. Such a rib 1, with the intermediate web extending substantially at right angles to the side 3 of the ship, would be found, generally speaking, amidships. At any point where the support 1 is a rib or frame of the vessel, the batten 5 must extend substantially parallel to the side 3 of the ship and the supporting cleat 6 is adapted to be attached to the flange 4 so as to hold or support the batten 5 in this relationship. The cleat 6 comprises preferably a malleable iron bracket having a pair of jaws 7 and 8 respectively adapted to embrace between them the flange 4 of the rib or angle iron 1. The inner side 9 of the jaw 7 is preferably a plane surface adapted to bear squarely against one side of the flange 4. The other jaw is provided with a vertical cylindrical lug or projection 10 on the free end thereof, and its inner surface 11 is preferably a plain surface converging slowly downwardly toward the opposite surface of the jaw 7, to provide a wedging surface between the jaw 8 and the web or flange 4.

A heavy wide flange or rib 12, integral with the jaws, is located at and constitutes the top of the jaws and this wide flange, extending away from the jaws, provides a seat 13 upon which the batten 5 rests, and, at the end of the seat 13, forms an upwardly extending finger 14 adapted to hold and retain the batten on its said seat 13.

Between the downwardly inclined surface 11 on the inner side of the jaw 8 and the web or flange 4, a wedge 15 is inserted, the wedge having a slowly tapered surface adjacent the inner slightly inclined surface 11 of the jaw 8.

40 To secure the cleat to the flange or web, the cleat is placed over the forward edge of the flange or web 4 so that the inner surface of the cleat bears against the front edge of the web or flange with the jaws 6 and 8 on opposite sides of the web 4, the cleat being held in the position in which it is to be secured. The flat inner side 16 of the finger 14 will be parallel to the side 3 of the ship at that point. The wedge 15 is then tightly driven in between the jaw 8 and the web or flange 4. The lug or projection 10 on the end of the jaw 8 provides a shoulder beyond which the wedge 15 cannot move, and prevents the slipping of the wedge 15 off of the end of the jaw 8 while the wedge is being driven in or after the cleat has been so secured to the web.

The flange or rib 12, integral with the cleat, makes the jaws very strong. A stiffening rib 17 is also preferably provided on the outer side of the finger 14, and the under side of the seat 13.

It will be plain that in order to support the cargo battens, the necessary number of batten cleats 6 are secured to the flange 4

of the ribs or angle irons 1 by driving wedges 15 between the jaws 8 and the flange 4, and that having been so secured, they provide a firm rigid but readily detachable support for the cargo battens 5. As a matter of fact, the aforesaid cleats having been secured to the angle irons or flanges thereof, are seldom removed or changed so that the longer they remain, the more firmly do they cling to the ribs or supports, because of the tendency of the metal parts of a vessel to rust.

It will be seen from the above that a very simple easily constructed cargo batten cleat readily secured to the ribs or angle irons of the sides of vessels is provided, and that by the use of them there is no necessity whatever of providing rivet or bolt holes, or cleat-supporting holes in or projections on the ribs themselves as is now practised in ship building. The expensive proposition of providing the flanges 4 with holes or similar provisions is done away with. Moreover, cleats, embodying my invention, may be secured at any point vertically of the ribs or angle iron 1 without regard to the construction of the rib itself.

In Fig. 4 is illustrated a slightly modified form of my invention. In this arrangement, the cleat 6' is one which is particularly adapted to be used with plain angle bars having flanges or webs 4' of the type shown in Fig. 5.

This form of cleat is exactly like the one above described, except that the seat 13 extends outwardly from the rear of the jaws instead of extending laterally from one of the jaws. This cleat is one which is adapted to support the batten at right angles to the forward edge of the web to which it is secured.

In Figs. 5 to 8 is shown another form or modification of my invention. In this construction, the cleat 6'' is particularly adapted for plain angle irons having vertical flanges or webs 4''. When the support or angle bar is a rib of a frame of a ship, the flange 4'' will always be at right angles to the center line of the vessel.

This cleat 6'' has a pair of jaws 7'' and 8'' respectively adapted to embrace between them the flange 4'' of the rib or angle iron 1''. The inner side 9'' of the jaw 7'' is inwardly curved to provide a clearance for the web 4'' and the end thereof is provided with a cylindrical surface 18 adapted to bear against one side of the flange or web 4''. The other jaw 8'' is provided with the vertical cylindrical lug or projection 10 on the free end thereof as previously described, and its inner tapered surface 11'' is substantially cylindrical and concentric with the axis of the cylindrical surface 18 of the jaw 7''. The surface 11'' is not quite cylindrical. Strictly speaking, it is conical, because it slowly con-

verges toward the opposite jaw to provide the wedging surface between the jaw 8' and the web 4'. In other respects the cleat 6'' is similar to that above described in connection with Figs. 1 to 4 and it is secured to the web by driving the wedge 15 in between the web 4' of the jaw 8'.

Inasmuch as the center of the curved surface 11' is substantially concentric with the center or axis of the tip 18 of the jaw 7', the pressure holding the cleat firmly on the rib 4 is always between the wedge 15 and the tip 18 of the jaw 7' at any angle at which the cleat is positioned with respect thereto.

15 When the web 4' makes an angle with the side 3 of the ship, as illustrated in Fig. 7, the cleat can be readily adjusted before driving the wedge 15 so as to bring the flat side 16 parallel to the side 3 of the ship. Fig. 5 20 shows one extreme position of the cleat with respect to a flange and Fig. 7 shows the other extreme limit of the adjustability of the cleat around the end of a rib or flange 4'.

In this case also the lug or projection 10 25 on the end of the jaw 8' prevents the wedge 15 from slipping laterally out from between the jaws either during the securing of the cleat to the web or after it is secured to the web and having been positioned prior to 30 driving in the wedge 15, there is no tendency of the cleat 6'' to cant or turn during the driving of the wedge, because the surface 11' is concentric with the surface of the tip 18. The pressure is always between the 35 wedge 15 and the tip 18.

In Figs. 9 to 11 is illustrated a fourth modified form of my invention. In this construction, the cleat 6''' is one which is particularly adapted to be used with angle 40 bars or supports having flanges or webs 4'' of the "bulb" construction or type. On the end of the rib 4'' is a bulb or rib 19 having a substantially cylindrical surface projecting from one side thereof. For use with this 45 type of flange, the jaw 8'' is provided with a tapering cylindrical or conical recess 20 near the end thereof and the wedge 15' is similarly provided with a conical tapering surface adapted to fit into the recess 20. 50 The other face of the wedge 15 is flat and is adapted to bear against the outer cylindrical surface of the bulb 19.

This cleat, in other respects, is like the cleat previously described and shown in 55 Figs. 5 to 8.

This cleat is secured to the bulb 19 of the flange or web 4'' by driving the wedge 15' in between the bulb 19 and the jaw 8'' with the flat surface of the wedge 15' against the 60 outer surface of the bulb 19 and the cylindrical or conical surface of the wedge seated in the slightly conical recess 20. In this construction, the wedge tends to drive the bulbed end of the rib 4'' in between the 65 outer end 18 of the jaw 7' and the back of

the jaw. It wedges or drives the bulbed end 19 in between the back of the recess between the jaws and the end 18 of the jaw 7'. In Figs. 9 and 11, this cleat 6''' is shown in its two extreme positions or adjustment with 70 respect to the various angles which the web 4'' may make with the sides 3 of the ship.

In Fig. 12 I have illustrated the supporting cleat 6'' above specifically described and illustrated in Figs. 5 to 8 of the drawings. 75

As it is adapted to be used on the ribs or frame work of a vessel to support cargo battens, this particular cleat has been selected to illustrate how all the cleats are adapted to be attached to their supports, 80 because it best lends itself to perspective illustration. It is to be understood, however, that all of the cleats are adapted to be attached to supports or ribs and it is also obvious that the supports may not necessarily be the ribs of the hull. In other words, they are adapted to be attached to the frame of a vessel in forming partitions or closures within the hold of a vessel where battens are usually employed.

When the 90 ribs or supports are of the type exemplified in Figs. 1 to 3, that is to say, when the supporting flange or web 4 is parallel to the side of the ship, there is no particular need for the angular adjustment of the cleat 95 around the forward edge of the web. Therefore, the cleat shown in Figs. 1 to 4 is particularly adapted for that purpose. It is also adapted for holding the battens of the supports used within the hold when the battens do not necessarily have to extend along 100 a curved line.

In all the embodiments of this invention as above set forth, the cleat may be secured to any point vertical of the flange of an 105 angle iron or rib of a vessel without special provisions therefor in the rib itself, and when the wedge is firmly driven in between the jaw coöperating therewith and the flange, the cleat is permanently and rigidly 110 secured to the outwardly extending flange of the rib, to hold the batten parallel to the side of the ship.

In all the embodiments of my invention above described, the end of the jaw between 115 which the flange or web the wedge is driven, is provided with a lug or projection on its tip or end, which prevents the web from slipping transversely or laterally out from between the jaws in adjusting the cleat or 120 in driving the wedge in position. Moreover, the engagement of the front edge of the web with the interior surface of the cleat prevents the cleat from turning or canting around a line passing through the center of 125 the wedge as an axis. Referring, for instance, to the first modification above described, the engagement of the forward edge of the web 4 with the interior of the inner surface of the cleat between the jaws, pre- 130

vents the cleat from turning about a line drawn through the center of the wedge and passing through the center of the end of the jaw 6, this being the line on which the cleat is frictionally supported on the rib. Similarly, in the other modifications shown, the engagement of the front edge of the web with the interior surface of the cleat between the jaws, prevents any lateral turning 10 of the cleat on the web to which it is clamped or wedged.

Inasmuch as in ship building, the outwardly extending flanges or ribs are disposed in planes at right angles to the center 15 line of the hull and the flanges of the ribs make a right angle or obtuse angle to each other, any of the cleats above described may be made in two forms, viz., a right handed form and a left handed form, and that form 20 may be selected which is best adapted to hold the battens parallel to the side of the ship, but such a change in, or adaptation of, the structure above described is fully contemplated by me and is fully within the aim and 25 scope of my invention.

Having thus described my invention, what I claim and desire to protect by Letters Patent of the United States is:

1. In a cargo batten cleat, the combination 30 of a pair of jaws adapted to embrace a flange of a rib or of a hull of a vessel, one of said jaws being adapted to bear against said flange and the other of said jaws being provided with a tapering surface and a wedge 35 adapted to be tightly driven between said last-mentioned jaw and said web whereby said cleat is firmly frictionally secured to said web.

2. In a vessel, the combination with a rib 40 having a flange or web, of a cleat having a pair of spaced jaws, one of which is in en-

gagement with one side of said web or flange, and a wedge tightly driven between the other of said jaws and said web.

3. In a vessel, the combination with a rib 45 having a flange or web, of a cleat having a pair of spaced jaws, one of which is in engagement with one side of said web or flange, a wedge tightly driven between the other of said jaws and said web, and means 50 to prevent said wedge from slipping transversely out from between said jaws.

4. In a vessel, the combination with a rib having a flange or web, of a cleat comprising 55 a pair of jaws, one of which has a plane surface adapted to bear squarely against one side of said web, the other having a plane surface slightly converging downwardly toward said other plane surface, and a wedge 60 tightly driven between said web and said last-mentioned surface.

5. In a vessel, the combination with a rib having a web, of a cleat comprising a pair of jaws, one having a surface to engage said web and the other having a surface slightly 65 converging toward said first-mentioned surface and spaced from said web, and a wedge tightly driven between said web and said converging surface.

6. In a vessel, the combination with a rib 70 having a web, of a cleat, a pair of jaws on opposite sides of said web, the front edge of said web bearing against the surface of said cleat between said jaws, one side of said web being in engagement with the end of one 75 jaw, and a tapering wedge driven between the other jaw and the opposite side of said rib.

In witness whereof, I have hereunto set my hand this 18th day of July, 1917.

JOSHUA W. ATLEE.
